(57) **CLAIM**

The ornamental design for a garment air connector, as shown and described.

DESCRIPTION

FIG. 1 is a perspective view of the invention.

FIG. 2 is a side elevational view of the invention.

FIG. 3 is a top plan view of the invention.

FIG. 4 is a bottom plan view of the invention.

FIG. 5 is a perspective view of the invention showing the environmental structure of the invention as deployed within a multi-layer garment; and,

FIG. 6 is a perspective view of the invention showing the environmental structure of the invention as manufactured in a roll of material.

Broken lines in the drawings are used to illustrate the environmental structure in which the article embodying the design is used and manufactured. The environmental structure forms no part of the claimed design.

The invention is identical as viewed from all sides, and thus only a single side is shown in the drawings.
